United States Patent

Des. 235,856
Patented July 15, 1975

235,856

DIVER'S DECOMPRESSION COMPUTER

Ralph B. Shamlian, San Francisco, Calif., assignor to
Farallon Industries, Inc., Belmont, Calif.

Filed Mar. 19, 1974, Ser. No. 452,615

Term of patent 14 years

Int. Cl. D10—04

U.S. Cl. D10—70

The figure is a top left perspective view of a diver's decompression computer showing my new design, the sides not shown being identical to those shown and the bottom being conventionally plain and unornamented.

I claim:

The ornamental design for a diver's decompression computer, substantially as shown and described.
